UNITED STATES PATENT OFFICE.

RALPH HUSH, OF JOHANNESBURG, TRANSVAAL, SOUTH AFRICA.

DISK OR PLATE FOR USE IN MILLS OR MACHINES FOR GRINDING OR PULVERIZING ORES AND OTHER MATERIALS.

Original application filed August 12, 1919, Serial No. 317,040. Divided and this application filed August 12, 1922, Serial No. 581,412.

To all whom it may concern:

Be it known that I, RALPH HUSH, a subject of the King of Great Britain, and resident of Johannesburg, Transvaal Province, 5 Union of South Africa, have invented certain new and useful Improvements in Disks or Plates for Use in Mills or Machines for Grinding or Pulverizing Ores and Other Materials, of which the following is a specification.

This invention relates to improvements in the grinding disks or plates used in mills or machines for grinding or pulverizing ore and other material, and more particularly 15 for use in those types of small mills or pulverizers in which the grinding is effected between fixed and rotating disks, employed in laboratories for reducing or pulverizing samples or small quantities of such materials. The invention, either in whole or in part, can, however, be adopted for use in mills or machines of larger size for reducing ore or like material.

This application is a division of application 25 Serial number 317,040, filed August 12, 1919.

The invention will be more fully explained with the aid of the accompanying drawings, in which—

30 Fig. 1 is a front view of one form of the fixed disk.

Fig. 2 is a sectional view of Fig. 1 on line $x-x$.

Fig. 3 is a front view of one form of the 35 rotating disk.

Fig. 4 is a sectional view of Fig. 3 on line $y-y$.

Fig. 5 is a front view of an alternative 40 form of the fixed disk.

Fig. 6 is a sectional view of Fig. 5 on line $z-z$.

Fig. 7 is a front view of an alternative 45 form of the rotating disk.

Fig. 8 is a sectional view of Fig. 7 on line $x-y$.

In the construction illustrated in Figs. 1 and 2, one form of the fixed disk 1 is shown, and in Figs. 3 and 4, one form of the rotating disk 2 is illustrated. This construction 50 of the disks is best suited for pulverizing comparatively coarse material. In constructing the disks 1, 2, I prefer to make them with

an unequal number of corrugations, the one having two corrugations more than the other. This ensures that the shearing edges 55 of the corrugations shall not all be in operation at the same time, thereby effecting a continuous distribution of the load or stresses during the complete revolution of the disk.

The fixed disk 1—see Figs. 1 and 2—has eight of the corrugations 3 which extend to within a short distance of the central inlet 4, in the direction of which they taper, as usual. The rotating disk 2—see Figs. 3 and 4—has ten of the corrugations 5 of the same length or approximately the same length as the corrugations 3 of the fixed disk 1.

In Figs. 5 and 6 I illustrate a type of fixed disk 6, and in Figs. 7 and 8, a type 70 of rotary disk 7, which are primarily intended for the pulverizing of comparatively fine material, the corrugations 8 in Figs. 5 and 6, and 9 in Figs. 7 and 8, being shortened or constructed so as to extend for a shorter distance from the inner edge 10 of the grinding faces 11 of the disks toward the centre; that is to say the inner portions of the corrugations are removed. This is desirable, as when reducing fine material 80 the long corrugations are not worn down sufficiently to maintain the necessary clearance between them to allow the grinding faces of the disks to assume their correct relative positions.

As shown in Figs. 1 to 4, and 5 to 8, the rotating disks 2 and 7 have two more corrugations than the fixed disks 1 and 6 respectively, viz, 10; 8. Provided, however, that each disk has an even number then 90 the rotating disk should have two more corrugations than the fixed disk.

It must, however, be understood that there must never be less corrugations on the fixed disk than two-thirds the number on the rotating disk; for instance two corrugations on the fixed disk and four on the rotating disk would not give the desired result, as two on the one would shear with two on the other simultaneously. The effect of my construction is that it prevents all the corrugations shearing simultaneously and gives a more uniform or symmetrical distribution of the stresses on the shaft, and also

prevents the tendency to separate or open the disks when the shearing is effected simultaneously by all the corrugations.

The fixed disks 1 and 6 may each, as shown, be provided with say two projections 12, 13, the one 12 preferably placed at one side of the central inlet 4, and the other 13 placed more or less diametrically opposite the first-mentioned one 12. These projections 12, 13, are tapped or provided with internal screw-threads which serve to accommodate the screws by which the disks 1 or 6 are attached to a stationary portion of the mill or grinding machine.

15 The rotating disks 2 and 7 may each, as shown, be provided with say three projections 14, 15, 16, arranged symmetrically around the centre of the disk. These projections are tapped or internally screw-threaded and serve to receive the screws which attach said rotating disks to the disk or other rotating part carried by the driving shaft of the mill or grinding machine.

20 In the case of mills in which grinding disks of large size are employed, that portion of the disk which lies between the inner ends of the corrugations can be replaced by a permanent centre piece, made of any suitable metal or material. This would obviate the waste of the material that would otherwise occur if the entire disk had to be discarded after it had been worn out. Expressed in other words the disk can be constructed of annular shape and be fitted with 25 a permanent centre piece, so that the annular outer part only would have to be discarded when worn out.

What I claim as my invention and desire to protect by Letters Patent is:—

1. A pair of grinding disks for use in a 40 grinding mill, one of which is fixed and the other arranged to co-operate therewith when rotated, both of said disks being constructed with inwardly tapering, outwardly extending ribs, said ribs being inclined from the periphery towards the centre in the direction of the backs of the disks and extending only a short distance from the inner edges of the grinding faces of the disks towards the centre of the disk, the rotating 45 disk having more ribs than the fixed disk, and the number of ribs on each disk being an even number, as set forth.

2. A pair of grinding disks for use in a 50 grinding mill, one of which is fixed and the other arranged to co-operate therewith when rotated, both of said disks being constructed with inwardly tapering, outwardly extending ribs, said ribs being inclined from the periphery towards the centre in the direction of the backs of the disks and extending only a short distance from the inner edges of the grinding faces of the disks towards the centre of the disk, the rotating 55 disk having two more ribs than the fixed disk, and the number of ribs on each disk being an even number, as set forth.

In testimony whereof I have signed my name to this specification in the presence of two subscribing witnesses.

RALPH HUSH.
